UNITED STATES PATENT OFFICE

LAURENCE R. WILDER, OF NEW YORK, N. Y., ASSIGNOR TO AMERICAN BROWN BOVERI ELECTRIC CORPORATION, OF NEW YORK, N. Y., A CORPORATION OF NEW YORK

INSULATOR STRUCTURE

Application filed May 29, 1926. Serial No. 112,471.

This invention relates to the insulators for high potential currents, such as are employed with transformers, oil switches and the like, and more particularly has to do with insulators or bushings of the oil-filled type.

5 Insulators of the general character mentioned include a metallic fastening member, usually in the form of an annulus, by which the porcelain cone or cylinder is attached to and held upon the container, tank or casing of the apparatus with which it is associated. This fastening member is held to the cone or cylinder by a cement joint, and the latter is at the exterior of the structure 10 where it is subjected to atmospheric conditions. Because of these conditions the cemented joint is susceptible to impairment and deterioration.

The primary object of the present invention is to provide an insulator of the class referred to which is so constructed as to afford a rigid connection between the cone or cylinder and the fastening member, which connection is such as to prevent liquid or 25 gas leakage between the parts, and also effectually to seal the insulator against seepage of the cement or compound employed in the joint connection.

The invention also contemplates an insulator structure wherein the joint between the cone or cylinder is disposed at the interior of the structure, thereby protecting the same against external atmospheric conditions, and insuring maintenance of the tightness of the 35 joint. This prolongs the life of the joint and renders the entire insulator structure more durable.

With these general objects in view, and others which will appear as the nature of the 40 improvements is better understood, the invention consists substantially in the novel construction, combination and arrangements of parts hereinafter fully described, illustrated in the accompanying drawings, and 45 finally pointed out in the appended claims.

For the illustration or delineation of the concept of the invention one practical embodiment thereof is disclosed herein. This however is not to be construed as imposing restriction or limitation upon the inven-

tion, the form shown being considered solely from the illustrative standpoint.

The annexed drawing illustrates a vertical transverse sectional view of an insulator structure embodying the improvements, and referring to the same in detail, the numeral 55 10 designates the insulating member, which is in the form of a cylindrical cone or sleeve, preferably formed of porcelain or other material adapted for the purpose. This cone 60 includes a plurality of depending skirts or bell portions, common to structures of this sort.

Associated with the insulating member 10 is a fastening member 12. This includes a 65 relatively broad base portion, substantially dome-shaped, which terminates in an outwardly extending attaching flange 13 having a series of perforations 14 for receiving bolts or the like, whereby the insulator structure 70 is fastened to the container, tank or casing of the apparatus with which it is to be associated.

The fastening member 12 has a centrally disposed opening 15, and through this opening 15 is passed the conductor when the insulator is applied to the apparatus. The opening 15 is surrounded by a vertically disposed elongated sleeve 16, which is relatively 75 long, and said sleeve fits within and is received by the lower end of the cone 10. The sleeve 16 is of less diameter externally than the internal diameter of the bore of the cone 10. A space therefore is provided between the sleeve 16 and the inner wall of 80 the cone 10. At the lower end of the interior of the cone 10 a shoulder 17 may be provided, whereby the space referred to, at the extremity of the bore of the cone 10 is reduced in diameter over the general diameter 85 of the bore. This provides a constricted area between the lower end of the cone 10 and the lower end of the sleeve 16, and the inner wall of the cone 10 below the shoulder 17 is provided with a series of grooves 18. 90 Within the space thus formed is disposed a suitable cementitious material 19. The characteristics of this material are such that it will provide not only a cementing action 95 between the sleeve 16 and the cone 10, but 100

also will provide a seal for the space to prevent the passage of fluid. In its cementing action the material 19 affords a rigid connection between the fastening member 12 and the insulating member 10, thereby uniting the parts into a substantially integral structure.

The lower end of the insulating member 10 may also be provided with a circumferential bead 20, designed to fit within a groove 21 formed in the dome-shaped portion of the fastening member 12. This provides a barrier which prevents outward flow of the material 19 as it is filled, in its plastic state, into the space between the sleeve 16 and the cone 10. Consequently, seepage of the cementitious compound is avoided.

From the foregoing description it will be apparent that with the material 19, acting as a cementing agent, and also as a seal, the fastening member 12 and the insulating member 10 are affixed rigidly with respect to each other. If a plastic cement is used and excessive temperatures are experienced in the use of the insulator, with the compound occupying the space between the sleeve 16 and the insulating member 10, it is apparent there is a hydrostatic head on this joint, and that seepage of the cement or compound material would not cause leakage, the material automatically refilling up to the point where the cement or compound became liquid. In the use of the grooves 18, it will also be apparent that the material 19, in engagement with these grooves, is effectually tied to the insulating member 10, thereby strengthening the joint to this further extent.

I claim:

40 Insulating means comprising a hollow insulating member open at both ends, and a fastening member therefor having a face fitting against the adjacent end face of said insulating member and an element extending into and being disposed in spaced relation with respect to the adjacent end of the latter to provide a space between said members for receiving cementitious material poured into said space in the plastic state 45 by way of the other end of said insulating member, the adjacent fitting faces of said members being complementary to each other and formed respectively to provide a seal of the male-and-female type operating to 50 confine said material against leakage while in such state between said faces.

In testimony whereof I have hereunto signed my name.

LAURENCE R. WILDER.
